APPARATUS FOR WASHING DISHES

Edmund J. Dwyer, Holyoke, Mass., assignor to
American Dishwashing Co. Inc., Holyoke, Mass.,
a corporation of Massachusetts

Application October 20, 1928, Serial No. 313,905

11 Claims. (Cl. 141—9)

My invention relates to dish washing and comprises broadly a novel apparatus for doing such work. Many of the advantages of my invention are particularly valuable in connection with 5 washing glasses.

One of the objects of the invention is to spray the dishes to be washed from a supply of fresh water. In a similar manner it is one of the objects of the invention to drain away all water 10 immediately after it has been used so that there will be no dirty water left in the machine or any part thereof and much less will there be any such water used for washing.

It is a further object of the invention to provide simple, inexpensive and reliable spraying means. More specifically it is intended that such means will require no other source of power for operation than that obtained from the pressure 15 of the water supplied for the washing operation. Still more specifically it is one of the objects of 20 the invention to utilize a rotary spraying device similar to the automatic rotary spraying devices used for sprinkling water on lawns and gardens.

Another object of the invention is to provide 25 automatic means for discontinuing the flow of water after a predetermined amount of operation. With the type of rotary spraying device hereinbefore mentioned which is operated by the pressure of the water, the rotation of the 30 spraying device is discontinued at the same time. With such an arrangement one of the advantages of draining away all used water immediately is that the heat of the water will warm the compartment in which the dishes are placed and 35 then, when the flow has ceased and the water has drained away, the heated compartment will rapidly dry the dishes.

It is also one of the objects of the invention to 40 provide a certain amount of liquid soap or cleansing solution or both with the water during the first part of the spraying operation and to use only fresh water during the last or rinsing part of the operation.

I have found some materials superior to others 45 for cleansing and one of the objects of the invention is to secure the superior cleansing results which can only be obtained by the use of a certain class of cleansing materials.

These and other objects of the invention will 50 more clearly appear from a consideration of the accompanying drawings in which:

Fig. 1 is a perspective view of a dishwashing machine in which are embodied certain structural features of my invention;

Fig. 2 is a vertical section of one form of valve used for automatically shutting off the supply of water;

Fig. 3 is a vertical section of a modified form of 60 valve;

Fig. 4 is a plan view of the lower rotary spraying device;

Fig. 5 is a vertical section taken on the line 5—5 of Fig. 4; and

Fig. 6 is a detailed view of the soap valve and 5 cam taken on the line 6—6 of Fig. 1.

In Fig. 1 the reference character 11 indicates a compartment in which the dishes to be washed may be placed. At the front of this compartment is shown a door 12 arranged to slide vertically in guides 13 provided at the sides of the opening to the compartment 11. At 14 there may be provided rails for the support of a tray 15 upon which dishes are placed. The tray 15 is adapted to slide into and out of the compartment 11 on the rails 14 so that the dishes may be placed on and taken off the tray 15 outside of the compartment where they may be more easily handled. A number of glasses 16 are shown on the tray 15 in position to be washed. 20

At substantially the central portion of the upper wall of the compartment 11 a pipe 17 is carried therethrough and is provided with a rotary spraying device 18 adapted to rotate as indicated by the arrow A under the force of the water 25 passing out of the orifices 19 in the direction indicated by the arrow B. Another pipe 20 passes through substantially the central portion of the lower wall of the compartment 11 and has mounted thereon a second spraying device 21 30 with orifices 22 for the discharge of the water.

The directions of the lower spray device 21 are opposite to those of the upper spray device 18, that is, the rotation is in the direction indicated by the arrow C under the action of the stream 35 of discharging water flowing in the direction indicated by the arrow D. It will be understood that the orifices in the upper spray device 18 serve two purposes in that they rotate the spray device and also direct the water downwardly so 40 as to spray the glasses. In a similar manner the orifices of the lower spray device 21 serve two purposes in that they rotate it and also direct the water upwardly to spray the inside of the glasses. In general, it is desirable that the lower spray 45 device rotate rather slowly as this gives the streams of water an opportunity to force the dirt from the surface. The tendency of rapid rotation is to so dissipate the energy of the streams of water that the resulting spray is more like a mist. 50 On the other hand, the upper spray, when used primarily for rinsing, as in the case of glasses, may rotate much more rapidly as the force of the water is not depended upon for removing the dirt. 55

The details of construction of the lower spray device, for example, may be as shown in Figs. 4 and 5. A bushing 23 is provided with an inwardly extending bearing flange 24, which flange has an aperture 25 therein through which a 60

fitting 26 may pass. The fitting 26 has a retaining hub 27 and is screwed into a hexagonal coupling 28 which unites it with the pipe 20. The fitting 26 is provided with a plurality of holes 26a for the passage of the water therethrough. A cap 29, having a plurality of orifices 29a at the top thereof is provided at its sides with threaded openings 30. The cap 29 is screwed into the bushing 23 and provides therewith a water chamber 31. A plurality of arms 32, 33 and 34 of pipe or tubing are threaded into the openings 30. To obtain the best results some care should be employed in the positioning of the orifices 22. As shown in Fig. 4, the arm 34 is provided with one orifice only, 22a, somewhat larger than the other orifices. This orifice is so positioned that the water flows out in a direction that is partly upward and partly horizontal. Due to the horizontal direction the moving part of the spray device comprising the bushing 23, the cap 29, and the arms 32, 33 and 34 is rotated in the direction indicated by the arrow C. Due to the upward direction this stream also washes the glasses which are in the outermost positions. The arm 33 is provided with orifices 22b which are arranged in three groups and all discharge the water in a vertical direction and therefore do not contribute to the rotation of the spray device but are useful solely for washing purposes. It will be noticed that the circular paths described by the orifices 22b are smaller in diameter than the circular path described by the orifice 22a and they do not therefore duplicate any of the work performed by the orifice 22a. The arm 32 is provided with two groups of orifices 22c which describe circular paths intermediate the paths described by the orifices in the other arms and therefore the streams of water from these orifices strike the glasses at different places than the other orifices. The specific arrangement of the orifices in the different arms as shown in this specific embodiment of my invention has been described somewhat in detail but it is obvious that other combinations and arrangements might also be employed.

The upper pipe 17 and the lower pipe 20 are connected together at a T 43 which is supplied by a pipe 44 through which the flow of water is controlled by means of an automatic valve 45. This valve will be described more in detail hereinafter but for the present it is sufficient to state that the valve is opened manually by means of a handle 46 and after the handle is released water will continue to flow through the valve until after a certain amount of operation the valve closes automatically. I have found that if the valve 45 operates for 20 or 30 seconds and discharges about two gallons of water very satisfactory results will be obtained. In general, cold water will not wash dishes clean. A temperature of 120 to 150 degrees F. is good but hotter water up to 180 or 190 degrees F. is better. It is to be understood, however, that the exact proportions set forth are not essential for fairly satisfactory results. In using more water or in operating the valve for a longer period both water and time will be used unnecessarily and wasted. In using the valve for a shorter period of time and using less water there is more likelihood of the glasses or other dishes not being thoroughly cleaned. The different factors governing the ideal length of operation and amount of water required are subject to so much variation that the above figures can at best be no more than approximations.

75 Provision may be made for the introduction of

soap and cleansing material into the pipe 20 at 47 through a pipe 48 having a check valve as indicated at 49 which prevents the water from flowing from the pipe 20 into the pipe 48 but permits the soap to flow from the pipe 48 into the pipe 20. Liquid soap may be supplied from a container 50. A suitable valve at 51 may be arranged to be operated by a cam 52a (Fig. 6) on an extension 52 of the handle 46 which opens the automatic valve 45.

The bottom of the compartment 11 is preferably given a pitch toward a pipe 53 which carries away the water immediately after it reaches the bottom of the compartment after being sprayed against the glasses.

In operation the glasses or other dishes are placed on the tray 16 and the tray is pushed into the compartment 11 on the rails 14. The door 12 is then closed and the valve 45 opened by means of the handle 46. At this time there is a charge of liquid soap and cleansing material in the pipe 20 which is trapped therein at the lower portion of the pipe. The liquid soap is trapped therein from the prior operation of the device in a manner which will be presently explained. The water from the valve 45 passes through the T 43 and then divides, part of it discharging through the upper spray device 18 and part of it passing through the pipe 20 carrying the soap before it into and out of the rotary spray device 21. After a relatively short period, possibly five seconds, the liquid soap and cleansing material has all been carried through the spray and the subsequent operation is a rinsing one.

With the opening of the valve 45 and the beginning of the flow of water through the pipe 20 the pressure of the water closes the check valve 49. The check valve is continuously held closed by the pressure of the water until the automatic valve 45 shuts off the supply. During the operation of the handle 46 the cam 52a of the arm 52 opens the valve 51 and permits the soap and cleansing material to flow into the pipe 48 until it is full although it cannot at this time flow beyond the check valve 49. The size and length of the pipe 48 is so chosen that it will hold just one charge of soap which may be about one ounce of the solution hereinafter described. When the automatic valve 45 shuts off, the check valve 49 is released and the soap flows into the pipe 20 and is there in position when the water is admitted for the next operation.

In the above described operation it is to be noted that only fresh water is sprayed against the glasses and the water is then immediately drained away from the machine without being used again. This method is in marked contrast to that of other machines now on the market, which all, as far as I know, use the same water over and over. The advantages of my method of operation are very great from a sanitary standpoint. There are many places where such sanitary washing is quite important, for example, at soda fountains, where the glasses actually touch the lips of the user. In fact where the water is hot enough the glasses or dishes are actually sterilized.

It is obvious that the soap may be led into the pipe 44 which is the common supply to both spray devices instead of into the pipe 20. In case such a connection is used there should be a trap for holding the supply of soap equivalent to the trap portion of the pipe 20. The advantage of such an arrangement is that the soap is 75

supplied to the upper spray device as well as to the lower one. In some cases such an arrangement would be desirable. But in the case of glasses used at soda fountains or where soft drinks are dispensed most of the dirt to be removed is on the inside of the glasses and there is very little need of soap for the upper spray device and the arrangement shown in Fig. 1 is just as satisfactory.

I have also found that certain ingredients in the soap or cleansing solution give superior results. If a considerable quantity of ordinary soap is mixed with the water suds are formed and the suds have insufficient body to satisfactorily clean dirty dishes. On the other hand most dirty dishes have a certain amount of grease or fatty substances thereon which is one of the ingredients from which soap is made. Caustic soda and caustic potash are each used for making soap from grease but where the hands come into contact with the material or are likely to come into contact with the material bicarbonate of soda is more satisfactory. The bicarbonate of soda with the hot water rapidly washes away the grease and performs the first or cleansing operation. It is nevertheless desirable to have a certain amount of soap in the water as liquid soap. Probably there are certain kinds of dirt on the dishes which can best be removed with a little soap and more particularly glasses will not dry clear with nothing but the bicarbonate of soda in the water. The following theory of operation is not intended to define or limit the invention but is merely set forth by way of explanation. When only bicarbonate of soda is used the glasses are perfectly clear and quite satisfactory if dried by hand. If they are permitted to dry by themselves a sort of bubble is formed and dries, leaving a spot or rather several spots on the glass so that it appears dirty and spotted. If a small quantity of liquid soap is added to the solution there is a tendency for the drops to run off and leave the glass clear. I have found that some types of liquid soap when sprayed against the glasses with hot water leave a blue glaze on the glass which is very difficult or almost impossible to remove. I have found that a small amount of soap tree bark in the water will permit the glasses to dry without spots and without an undesirable glaze.

While I do not wish to confine myself to exact proportions, I have found that a satisfactory cleansing solution may comprise four ounces of bicarbonate of soda in two quarts of water together with one-quarter ounce of soap tree bark. The soap tree bark may be steeped in the water or hot water may be merely added to it and allowed to stand. It is to be understood that the undissolved soap tree bark is removed by decantation or filtering. In comparing the relative values, for the purposes for which they are selected, of the materials hereinbefore mentioned for changing grease to soap, the caustic soda is perhaps the most efficacious and the bicarbonate of soda the least harsh on the hands. Other alkalies may be substituted for soda such as potash, ammonia and lime; and other salts of soda or salts of other alkalies may also be used such as tri-sodium phosphate and borax or sodium borate. In general all alkalies or substances of an alkali nature may be said to be the equivalent of the substances specifically mentioned.

The detailed construction of one form of automatic valve may best be understood by refer-

ence to Fig. 2. A cylindrical casing 61 may be provided with an opening 62 at its upper end for the passage thereinto of water from some suitable source of supply and may be provided at its lower portion with an opening 63 for the outward passage of the water. Near the middle portion of the casing 61 there is rigidly held in place a disc 64 which has openings 65 provided therein which serve as guides for rods 66 attached to the moving portion of the valve. The disc 64 also has a plurality of openings 64a which permits the water to flow freely at all times from one side of the disc to the other. Secured to the disc 64 or integral therewith is a cylinder 67 in which a governor 68, which also may be of cylindrical form, is adapted to slide, the relative diameters being such that there is a small clearance between the governor 68 and the cylinder 67. The purpose of this clearance is to permit the water to move out of the cylinder 67 around the governor 68 at a slow rate only and thus to act as a hydraulic governing device to regulate the speed of the movement. The governor 68 is secured to a governor rod 69 in any suitable manner which governor rod is threaded in a flange 70 which is secured to the guide rods 66. An ear or bracket 71 extends from the wall of the casing 61 and is provided with an opening 72 through which the governor rod 69 passes and which serves as a guide therefor. A valve disc 73 is secured to the lower ends of the rods 66 and moves therewith. An annular valve face 74 on the valve disc 73 cooperates with a valve seat 75 in the casing 61. A cylindrical member 76 depends from the valve disc 73 and fits in the opening 63 and serves to guide the moving parts in their reciprocation. The member 76 may be provided with openings 77 to permit the water to flow readily into the opening 63. At the upper portion of the moving part of the valve an operating disc 78 may be provided which threads over the governor rod 69 and acts as a locknut to hold the flange 70 in its adjusted position and also provides means for the operation of the valve. The upward movement of the disc 78 and associated parts is limited by the bracket 71.

A rod 79 passes through the casing 61 and has a manually operated handle 46 secured to one end thereof and a cam 82 secured to the other end thereof for engagement with the disc 78. A spring 83 returns the handle to its inoperative position after it has been released by the operator. A check valve is provided for the lower end of the cylinder 67 which may comprise a ball 84 resting on a seat 85 at the upper end of an opening 86. A suitable cage 87 may be provided to prevent the ball from moving away from its position when it is lifted by the water from its seat.

The operation of the valve 45 is as follows. The operator turns the handle 46 and thus lifts the cam 82 and moves the disc 78 upwardly. This lifts the valve disc 73 from its seat and also draws the governor 68 to the upper end of the cylinder 67. The handle 46 is then released and the spring 83 restores it together with the cam 82 to its inoperative position. As the governor 68 is moved upwardly in the cylinder 67 the water flows into the cylinder between the governor and the cylinder because of the clearance between them and it also flows into the lower end of the cylinder through the opening 86 because the ball 84 is forced upwardly away from the seat 85. The opening 86 is considerably larger than the clearance between the governor 68 and 78

the cylinder 67 and the water therefore flows into the cylinder much more readily than it could if the opening 86 were closed.

With the movable part of the valve in the upper position the water flows through the opening 62 in the direction indicated by the arrows E and out through the opening 63. The pressure of the water above the valve disc 73 is somewhat greater than the pressure at 63 below the valve disc and there is therefore a tendency for the water to force the valve disc 73 toward the valve seat. The rapidity of this movement is governed by the throttling action exercised on the water in passing through the passage between the cylinder 67 and the governor 68. It is to be noticed that in the downward movement of the governor the ball 84 closes the opening 86 and no water passes through at this opening. The length of operation of the valve may be regulated by adjusting the position of the governor 68 on the rod 69. After the valve face rests on the valve seat 75 the water ceases to flow until the valve is again put into operation manually by the movement of the handle 46.

25 A somewhat different type of valve is shown in Fig. 3. A cylindrical casing 91 has a valve seat 92 in its lower portion. A movable valve member carries a packing 93 at its lower portion which cooperates with the seat 92 and at its upper portion is provided with a disc 94 which divides the cylinder 91 into two chambers 95 and 96. An opening 97 provides for the admission of the water into the lower chamber 95 and another opening or discharge passage 98 carries the water away when the valve has opened at the seat 92. An auxiliary passage 99 may be provided which at its lower end is connected with the passage 98 and at its upper end is separated from the upper chamber 96 by a pilot valve 100. A handle 101 may be provided for the operation of the pilot valve 100 and serves to open the pilot valve when moved in any direction. Springs 102 and 103 are used to restore the valve 100 to its seat after the handle 101 is released. A by-pass 104 may be provided in the disc 94 to permit the water to flow at a very slow rate from the lower chamber 95 into the upper chamber 96 when a difference in pressure exists therebetween.

The operation of the modified form of valve shown in Fig. 3 is as follows. It will be assumed that the valve at 92 has been closed for some time and the water pressures in the upper chamber 96 and the lower chamber 95 are therefore the same. The handle 101 is moved and the valve 100 opened which thus permits the water from the upper chamber 96 to flow through the auxiliary passage 99 into the passage 98. The pressure of the water in the chamber 95 will then lift the disc 94 and open the valve at 92. After the pilot valve 100 is permitted to close the water will continue to flow through the main valve at 92 and also slowly through the by-pass 104 into the upper chamber 96. As the chamber 96 again fills with water the disc 94 together with the movable portion of the valve is slowly forced downward and the main valve is closed at 92.

It is to be understood that the above described embodiments of the invention are for the purpose of illustration only and various changes may be made therein without departing from the spirit and scope of the invention as defined in the subjoined claims.

I claim as my invention:

1. In a dishwashing machine, a closed compartment, a dish tray in substantially the middle

portion thereof, a rotary spray device in the lower portion of said compartment, a second rotary spray device in the upper portion of said compartment, said devices being adapted to be rotated by water supplied thereto under pressure, pipe connections for each of said devices, a time-controlled valve for controlling the flow of water to said connections of the type adapted to automatically close after a predetermined amount of operation, a source of supply of liquid soap, means including a check valve for conducting a supply of said liquid soap to the pipe connections for said lower spray device, and means operated by said automatic valve for opening said source of supply to said first-named means to permit a charge of liquid soap to flow toward said check valve.

2. In a dishwashing machine, a washing compartment having an outlet, an inlet adapted to be fed with a fluid under pressure, a sprayer disposed in the washing compartment, a communicating means connecting the inlet with the sprayer, a timing valve in the communicating means of a type adapted to close automatically a predetermined time after it is opened, a second means for supplying a washing substance periodically, pipe connections between said second means and said communicating means, a valve in the said pipe connections for controlling the supply of said washing substance, means in said pipe connections for preventing reverse flow therethrough, and means by which one of the valves is adapted to operate the other valve.

3. In a dishwashing machine, a washing compartment having an outlet, an inlet adapted to be fed with a fluid under pressure, a sprayer disposed in the washing compartment, a communicating means connecting the inlet with the sprayer, a time-controlled valve in the communicating means of a type adapted to close automatically a predetermined time after it is opened, a second means connecting with the communicating means for feeding a washing substance thereto periodically, a valve in the second mentioned means, means by which one of the valves is adapted to operate the other valve, and a check valve in the second mentioned means between the second mentioned valve and the communicating means.

4. In a dishwashing machine, a washing compartment having an outlet and an inlet, a pipe leading to the inlet, means connected to said pipe to feed a washing substance thereto, and means connected to said pipe to supply subsequently the pipe with a washing fluid whereby the combined washing substance and washing fluid will serve to wash the dishes and the continued flow of the washing fluid will subsequently rinse the dishes, a valve for the first mentioned means, a valve for the second mentioned means, and means by which one of the valves is adapted to operate the other valve, and means for automatically preventing the reverse flow of said washing substance in said first-named means when both valves are open at the same time.

5. In a dishwashing machine, a washing compartment, an outlet for continuously carrying away the used water, a rotary spray device in said compartment, an inlet connected to said rotary spray device, means for supplying soap to said inlet, a valve for controlling the supply of soap to said inlet, means for supplying water to said inlet, a second valve for controlling the supply of water to said inlet, means including a single operating handle for opening both valves simul-

taneously, and automatic means for closing both valves automatically.

6. In a dishwashing machine, a washing compartment, means for supporting dishes to be washed therein, a rotary spray device positioned so as to spray the dishes on said supporting means and adapted to be rotated by pressure of the water supplied thereto, pipe connections for supplying water under pressure to said spray device, a valve in said connections having manually operable means for opening said valve and said valve having self-contained automatic means also moved by the pressure of the water to close said valve and discontinue the application of pressure for the rotation of said spray device a predetermined time after the opening thereof, said automatic means being operable solely by the pressure of the water supplied to said valve, valve means for supplying a washing substance in fluid form to said pipe connections and including means for operating the same, and means operated automatically by the manipulation of the machine for initiating its operation to operate said valve operating means automatically.

7. In a machine for automatically washing dishes for a predetermined time and then automatically discontinuing the washing operation, in combination with a washing compartment and means for supporting the dishes to be washed therein, a spray device for washing the dishes on said supporting means rotatable by the pressure of the liquid supplied thereto, a timing valve through which said liquid flows to said spray device and operable by the pressure of the liquid supplied thereto for discontinuing said flow of liquid and the operation of said spray device, connections to a single source of liquid under pressure for operating said timing valve and supplying said spray device, means for introducing a predetermined amount of liquid cleansing substance into the connections to said spray device including a valve and its operating means, and means automatically operated by the manipulation of said machine to initiate its washing operation for controlling the admission of said cleansing substance to said connections.

8. In a machine for automatically washing dishes, the combination of a washing compartment, means for supporting the dishes to be washed therein, means operable by liquid under pressure for ejecting said liquid as a washing fluid in the form of a spray against said dishes and for moving the spraying means and said dish-supporting means relatively, a valve including means as a part thereof directly subjected to the pressure of the liquid flowing through said valve for moving said valve and discontinuing said relative movement and liquid ejection after a predetermined period of time, means for introducing a detergent into the liquid ejected onto the dishes including a valve and its operating means, means automatically operable by the manipulation of said machine for initiating its operation to operate said valve operating means automatically, and manually operable means for initiating the operation of said machine.

9. In a machine for automatically washing dishes, the combination of a washing compartment, means for supporting the dishes to be washed therein, spraying apparatus having means operable by a liquid under pressure for

ejecting said liquid as a washing fluid in the form of a spray against said dishes and for moving the spraying apparatus and said dish-supporting means relatively, a valve including means as a part thereof directly subjected to the pressure of the liquid flowing through the valve for controlling the flow of said liquid to said spraying apparatus and operated by the pressure of said liquid flowing therethrough for discontinuing said relative movement and liquid ejection after a predetermined period of time, connections for conveying said liquid to said spraying apparatus, manually operable means for initiating the operation of said machine, means for supplying a liquid detergent into said liquid connections leading to said spraying apparatus including a valve and its operating means, and means automatically operated by the manipulation of said machine for initiating its washing operation to actuate said valve operating means automatically.

10. In a machine for automatically washing dishes, the combination of a washing compartment, means for supporting the dishes to be washed therein, a spray apparatus mounted for rotation in said compartment and having means operable by a liquid under pressure for ejecting said liquid as a washing fluid against said dishes and for rotating said spray apparatus relatively to said dish-supporting means, connections for conveying said liquid to said spraying apparatus, a valve including means as a part thereof directly subjected to the pressure of the liquid flowing through said valve and operable to control the flow of said liquid to said spraying apparatus and operated by the pressure of said liquid flowing therethrough for discontinuing said rotary movement and liquid ejection after a predetermined period of time, manually operable means for initiating the operation of said machine, means for supplying a liquid detergent into the connections between said valve and said spraying apparatus and including a valve and its operating means, and means automatically operated by the manipulation of said machine for initiating its washing operation to operate said valve operating means automatically.

11. In a machine for automatically washing dishes, the combination of a washing compartment, means for supporting the dishes to be washed therein, spraying apparatus having means operable by liquid under pressure for ejecting said liquid as a washing fluid in the form of a spray against said dishes and for moving the spraying apparatus and said dish-supporting means relatively, a valve including means as a part thereof directly subjected to the pressure of the liquid flowing through the valve for controlling the flow of said liquid to said spraying apparatus and operated by the pressure of said liquid flowing therethrough for discontinuing said relative movement and liquid ejection after a predetermined period of time, means for introducing a detergent into the liquid ejected onto the dishes including a valve and its operating means, means automatically operated by the manipulation of said machine for initiating its washing operation to operate said valve operating means automatically, and manually operable means for initiating the operation of said machine.

EDMUND J. DWYER. 70
